UNITED STATES PATENT OFFICE.

JEFFERSON C. GIBSON, OF CHICAGO, ILLINOIS.

COMBUSTION CONTROL.

Application filed June 25, 1927. Serial No. 201,416.

This invention relates to improvements in combustion controls and more especially to safety means for stopping the operation of the fuel feeding means in the event that the combustion fails to start within a predetermined period of time after the burner has been put into operation.

In automatically operated furnaces, a hazard arises when the fuel fails to ignite properly. The combustion chamber becomes filled with an accumulation of explosive gases which cannot be carried off by the cold stack and if the gases are then ignited, a disastrous explosion is liable to occur.

In this invention, a time element circuit breaker is incorporated in the combustion or stack thermostat, which in itself is a safety control, in such manner that the stack thermostat switch is permanently opened when the system does not function properly. After the switch has been opened, it requires manual restoration, so that attention is called to the faulty operation of the furnace.

The main objects of the present invention are to provide a simple, reliable safety combustion control system; to provide a combustion control in which the stack thermostat switch is utilized for the time element circuit breaker; to provide an adjustable circuit breaker which may be adjusted to suit the operation of the particular furnace with which the control is used; to provide a control in which the stack thermostat is also utilized for controlling the ignition; to provide a control in which both the motor circuit and the ignition circuit are opened by the same safety device; and to provide a simple form of an adjustable single acting circuit breaker for a combustion control system.

An illustrative embodiment of this invention is shown in the accompanying drawings, in which:

Figure 1 is a diagrammatic illustration of the automatically controlled combustion system.

Fig. 2 is a plan section through the stack, showing an outside view of the stack thermostat.

Fig. 3 is a face view of the stack thermostat with the cover removed.

Fig. 4 is a view of the stack thermostat with the housing shown in section and the

switch arm rotated into the vertical position for the purpose of illustration.

Fig. 5 is a detailed section taken on the line 5—5 of Fig. 3.

Fig. 6 is a view of the upper portion of the parts shown in Fig. 3 showing the switch in the dropped position.

In this invention, the mercury switch bulb of the stack thermostat is pivotally mounted on the thermostat switch arm, and is releasably held thereon in normal position. The switch bulb is released so that one end drops down by an emergency operation of an electro thermal device comprising a bi-metallic bar which is heated by means of a resistance coil placed in series in the starting circuits.

Referring to the drawings in Fig. 1, a furnace 7 is provided with a burner 8, which is operated by the motor 9 for supplying the fuel and air requisite for supporting the combustion. When the burner is started, the fuel mixture is ignited by means of a spark gap device 10 which is supplied with high tensioned current from the transformer 11.

The combustion or stack thermostat 12 is mounted in the stack 13, and has a mercury switch bulb 14. The bulb is provided with three contact points 15, 16 and 17, at one end, and with two points, 18 and 19, at the other end, as is more clearly shown in Fig. 3. The first three contacts are electrically connected by the mercury globule when the switch arm is in the normal or "cold" position, in which position the bulb is inclined to the left; and the two points at the opposite end are connected when the switch arm is in the running or "hot" position in which the bulb is inclined to the right, as shown in dotted lines in Fig. 3.

The room thermostat 20 is provided with a switch 21 which is closed at low room temperatures. One side of the switch 21 is connected to one pole of the current supply switch 22, and the opposite side of the switch 21 is connected by means of the wire 23 to the contact 19. A branch wire 24 leads from the wire 23 to the electrothermal circuit breaking element 25, which is then connected by the wire 26 to the contact 16, with the result that the room thermostat is connected to both sides of the switch. Contacts 17 and 18, which are likewise at the opposite sides of the switch, are joined and connected by the wire 27 to the switch 28.

of the boiler thermostat 29; and from the switch 28 by means of the wire 30 to one terminal of the motor 9. The opposite terminal of the motor is connected by the wire 31 to the opposite side of the supply switch 22. Then the primary winding 32 of the transformer 11 is connected from the supply wire 31 to the one end contact 15 by means of the conductor 33.

10 In the cold position, the three contacts at the left are connected, and when the room thermostat switch 21 is closed, the starting circuits are completed. Connection is made from the supply switch through the room thermostat wire 23, through the branch 24, the heating element 25 to the contact 16. From this contact, a complete connection is made through the boiler thermostat and the motor by means of the wires 27, 30 and 31, 15 and also a complete connection through the primary coil of the transformer 11 by means of the wire 33. The igniter will then be energized to ignite the fuel mixture, and the motor 9 put into operation to supply the 20 same. As will be described hereinafter, the heating coil 25 is effective for releasing the switch bulb 14 so that all circuit completing connections are opened after the coil has been in the starting circuit a predetermined 25 period of time. If the combustion starts properly, the switch rod of the stack thermostat will be rotated so that the bulb is inclined to the right before the safety time period has elapsed and before the switch has been opened by the heat from the coil 25. The circuits, after the stack thermostat has operated, are then in the running condition in which the room thermostat is still connected in series with the boiler thermostat 30 and the motor 9, but with the igniter disconnected.

The stack thermostat comprises a housing 36 which is provided with a removable cover 37 and a boss 38 on the inner side, which 45 projects into an opening in the stack 13 when the thermostat is mounted in position. A bi-metallic coil 39 is anchored at one end to the boss 38, and is secured at the outer end to the rod 40.

50 The rod 40 is rotatably mounted in the boss 38 and carries, on the end which projects into the housing, the switch arm 41. The switch arm is rotatable on the rod and is frictionally connected thereto by means 55 of the spring 42 which is coiled around the rod and pressed between the switch arm and the adjusting nut 43, which is threaded on the end of the rod, to press the switch arm against the shoulder provided by the nut 44 which is also threaded on the rod 40.

The switch arm projects at either side from the mounting on the rod, and the lower end engages the stops provided by the posts 45 which are fixed in the housing 36. The 60 bi-metallic coil 39 may twist in either direc-

tion through a greater arc than the permissible arc of movement of the switch through the frictional connection but starts to move the arm on the first reversal of the movement.

70 The mercury switch bulb is gripped in a clip 46 which is pivoted on the post 47 which is rigidly secured to the upper end of the switch arm. The clip carries a weight 48 at one side for rotating the clip and bulb counterclockwise to the "off" position shown in Fig. 6. Under normal operating conditions, the bulb is held in transverse relation to the switch arm by means of the pin 49 in the end of the bi-metallic bar 50.

75 The bar 50 is anchored at the lower end to the lower end of the switch arm and slidably engages with the post 47. The clip is provided with an arcuate portion 51 having an aperture 52 into which the pin 49 is engaged to hold the bulb from turning. In 80 restoring the switch, the bulb is merely lifted at one end and the pin enters the hole as soon as it is registered therewith.

85 The electrical heating element 25 is clamped between mica strips 53 which are clamped to the midportion of the bar 50 by the clamp 54. The arrangement is such that when the bar 50 is heated by the element 25, it is flexed so that the upper end is moved 90 outwardly to retract the pin 49 from the aperture 52 to release the switch bulb.

95 This outward movement is resiliently opposed by the spring 55 which is coiled around the post 47 and seats on the adjusting nut 56 which is threaded on the outer end of the post. By adjusting the nut 56 the period of time in which the starting current flowing through heating element will 100 flex the bar to release the switch may be 105 determined.

110 While but one specific embodiment of this invention has been herein shown and described, it will be understood that details of the construction shown may be altered or omitted without departing from the spirit of this invention as defined by the following claims:

I claim:

1. A thermostatic control instrument having an arm movably responsive to temperature changes, a mercury bulb switch mounted on said arm and releasably held in fixed position thereon, and electrothermal means mounted on the arm for releasing said switch, said switch being normally urged to an open position.

115 2. A thermostatic control instrument having an arm movably responsive to changes in temperature, a mercury switch bulb pivotally mounted on the arm, a catch for holding the bulb in a fixed but unbalanced position on the arm, and electrothermal means for moving the catch to release the bulb.

120 3. A thermostatic control instrument hav-

ing an arm movably responsive to changes in temperature, a mercury switch bulb pivotally mounted on the arm, a flexible member anchored to the arm and engaged with the switch bulb to hold the bulb in normal position on the arm, and an electric heating element for flexing said member to disengage the same from the switch bulb, said bulb being normally urged to an open position.

4. A thermostatic control instrument having an arm movably responsive to changes in temperature, a clip for carrying a mercury switch bulb pivotally mounted on the arm, a bi-metallic bar anchored to the arm at one end and engaged with the clip at the free end to hold the switch bulb in fixed position on said arm, an electric heating element for flexing the bar to disengage from the clip, and an adjustably tensioned spring for opposing said flexing to regulate the timing, said bulb being normally urged to an open position.

5. A thermostatic control instrument having an arm movably responsive to changes in temperature, a post fixed on said arm, a mercury switch bulb having a clip pivoted on said post, a bi-metallic bar anchored at one end to the arm and engaged at the other end with the clip to hold the clip from turning on the post, an adjustable coil spring

on the post pressing the bar into engagement with the clip, and an electric heating element mounted on the bar to flex the same against the tension of said spring to disengage from the clip, said bulb being normally urged to an open position.

6. In a stack thermostat having a bimetallic member in the stack connected to a pivotally mounted switch arm for controlling the rotative position thereof, a mercury switch bulb having a clip pivotally mounted on the arm, said clip having a segmental portion, a bi-metallic bar anchored at one end to the switch arm and having a pin at the movable end for engaging the clip to hold the switch bulb in normal position on the arm, the pin being adapted to ride on the segmental portion of the clip when disengaged from holding the clip.

7. A thermostatically controlled instrument having an arm movably responsive to temperature changes, a switch mounted on said arm and arranged to be opened and closed according to the position of said arm, and electro-thermal means mounted on said arm and arranged to independently operate said switch.

Signed at Chicago this 18th day of May, 1927.

JEFFERSON C. GIBSON.
